(57) **CLAIM**

The ornamental design for a storage case for insoles as shown and described.

DESCRIPTION

FIG. 1 is a top front right perspective view of a storage case for insoles in accordance with said design;

FIG. 2 is a top rear left perspective view of the storage case for insoles of FIG. 1;

FIG. 3 is a bottom front right perspective view of the storage case for insoles of FIG. 1;

FIG. 4 is a front end view of the storage case for insoles of FIG. 1;

FIG. 5 is a rear end view of the storage case for insoles of FIG. 1;

FIG. 6 is a right side view of the storage case for insoles of FIG. 1;

FIG. 7 is a left side view of the storage case for insoles of FIG. 1;

FIG. 8 is a top plan view of the storage case for insoles of FIG. 1;

FIG. 9 is a bottom plan view of the storage case for insoles of FIG. 1; and,

FIG. 10 is a top right front perspective view of the storage case for insoles of FIG. 1, in an open configuration.

The portions shown in broken lines do not form part of the claimed design.

1 Claim, 8 Drawing Sheets
